UNITED STATES PATENT OFFICE.

SILAS M. HESS, OF BLOOMSBURG, PENNSYLVANIA.

TORCH FOR DESTROYING INSECTS.

SPECIFICATION forming part of Letters Patent No. 727,628, dated May 12, 1903.

Application filed May 22, 1902. Serial No. 108,566. (No model.)

To all whom it may concern:

Be it known that I, SILAS M. HESS, a citizen of the United States, residing at Bloomsburg, in the county of Columbia and State of Pennsylvania, have invented a new and useful Torch for Destroying Insects, &c., of which the following is a specification.

This invention relates generally to torches, and particularly to that class intended for the destruction of insects, larvae, and the like upon fruit-trees, shrubbery, &c.

The object of the invention is to provide a torch of this character which shall be simple of construction, efficient and durable in use, and that shall be capable of absorbing and retaining a large amount of inflammable material for the purpose designed.

With these and other objects in view, as will appear as the nature of the invention is better understood, the same consists in the novel construction and combination of parts of a torch for destroying insects, &c., as will be hereinafter fully described and claimed.

In the accompanying drawings, forming a part of this specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof, and in these drawings—

Figure 1 is a view in elevation of a cage or holder for the absorbent material for containing the inflammable material used for burning insects and the like. Fig. 2 is a similar view showing the cage with the absorbent material therein and the handle or staff associated therewith.

Referring to the drawings, 1 designates generally the cage, and 2 the staff or handle. The cage in this instance is shown as being constructed of three pieces of wire bent centrally of their length to present a substantially elliptical cage, the straight portions of the wires being held assembled by a binder 3, spirally coiled thereabout. While the said binder will be thoroughly efficient for hold-

ing the wires assembled, it is to be understood that the same may be otherwise assembled, as by thimbles or by being brazed together, and still be within the scope of the invention. At the crest of the bend one of the wires is provided with an eye 4, through which the bends of the other wires are passed, as clearly shown in both of the figures, this arrangement being adopted on account of its simplicity and the ease with which such a cage can be constructed. The shank 5, formed by the assembled straight portions of the wires, is of such length as to remove possibility of the flame from reaching the staff 2, which, as usual, will be constructed of wood and in a plurality of telescopic or readily-assembled sections 6 and 7, of which there may be any preferred number.

The absorbent 8 for the coal-oil or other inflammable substance employed is composed of a refractory substance, preferably asbestos reduced to pulp, and then disposed within the cage. In the use of the device the asbestos pulp will be saturated with coal-oil or the like and when ignited will burn for a considerable period of time, the oil from the interior of the asbestos being gradually fed to the exterior, as will be readily understood.

With a torch such as described all insect life when developed or in embryo will readily and effectively be destroyed without danger to the operator of being burned, inasmuch as the asbestos pulp will occlude the oil and only yield it up as requisite.

By reason of the elliptical shape of the cage the flames from the oil will burn to a point which may thus readily be directed against the insects to be destroyed, thereby obviating the danger of burning unnecessary portions of the tree or shrub upon which such insects may have harbored.

Having thus fully described my invention, what I claim as new, and desire to secure by Letters Patent, is—

A torch for destroying insects, comprising a cage and a body of absorbent refractory material held therein, the cage being composed of a plurality of wires bent upon themselves and formed into a fusiform structure terminating in an elongated shank formed by

straight continuations of the cage members, | my own I have hereto affixed my signature in
the crest of one of the members being pro- | the presence of two witnesses.
vided with an eye in which are disposed the |
crests of the other members, a binder for as- |
sembling the shank members, and a handle |
associated with the shank.
In testimony that I claim the foregoing as |

SILAS M. HESS.
